[57] **CLAIM**

The ornamental design for a vehicle window and windshield sunshade, as shown and described.

DESCRIPTION

FIG. 1 is a front elevational view of the vehicle window and windshield sunshade showing our new design;

FIG. 2 is a rear elevational view thereof;

FIG. 3 is a right view thereof;

FIG. 4 is a left view thereof;

FIG. 5 is a top plan view thereof;

FIG. 6 is a bottom plan view thereof; and,

FIG. 7 is a front elevational view thereof, showing the design in use.

The dotted line showing of a vehicle window and door are for illustrative purposes only and form no part of the claimed design.
